(57) **CLAIM**

The ornamental design for portion of a footwear sole, as shown and described.

DESCRIPTION

FIG. 1 is a perspective view of the portion of a footwear sole embodying the new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

FIGS. 1-6 show portions of an upper and an outsole in broken lines. The upper and outsole are shown for environmental purposes and do not form any part of the claimed design.
